PRESSURE EQUALIZER

James A. Lupfer, Tulsa, Okla.

Application December 20, 1940, Serial No. 370,953

7 Claims. (Cl. 138—31)

This invention relates to pressure equalizers, and more particularly to a liquid pressure equalizer for use in pipe lines for reducing pressure variations in the pipe line caused by the variable delivery of liquids from a reciprocating pump.

An object of the present invention is to provide a pressure equalizer which will absorb pressure variations in pump discharge lines, thereby making it possible to operate at materially higher pressures in such lines and with a greater factor of safety.

Another object of the present invention is to provide a pressure equalizer wherein a plunger is provided which is acted upon by the pressure in the line and by spring pressure to equalize the line pressures, and which provides novel features to avoid excessive friction during the operation of the plunger; to insure a tight seal between the plunger and its cylinder; and means whereby the pressure exerted by the springs on the plunger may be regulated as required.

With these and other objects in view, as may appear from the accompanying specification, the invention consists of various features of construction and combination of parts, which will be first described in connection with the accompanying drawings, showing a pressure equalizer of the preferred form embodying the invention, and the features forming the invention will be specifically pointed out in the claims.

In the drawings:

Figure 1 is a vertical section through the improved pressure equalizer.

Figure 2 is a horizontal section through the equalizer taken on the line 2—2 of Figure 1.

Figure 3 is an enlarged detail section taken on the line 3—3 of Figure 1.

Figure 4 is a cross-section taken on the line 4—4 of Figure 1.

Referring more particularly to the drawings, the improved pressure equalizer includes a cylinder, 1, the lower end of which is attached by a suitable attaching flange or collar 2 to the pipe line (not shown) with which the pressure equalizer is to be associated, and the lower end of the cylinder opens into the pipe line so as to permit the pressure fluid flowing through the pipe line to enter the cylinder and engage the lower end of the plunger structure 3. The plunger 3 reciprocates in the cylinder 1 and has its upper end connected to a piston 4 which reciprocates in the enlarged portion 5 of the cylinder structure.

A plurality of springs 6 are mounted in the enlarged portion 5 of the cylinder structure and engage against the upper side of the piston 4 and

the under side of the cylinder head 7 for exerting pressure against the piston 4 and consequently against the plunger 3, in a reverse direction to the pressure exerted against the plunger 3 by the pressure fluid acting thereon. Suitable means are provided for regulating the tension of the springs 6 and consequently regulating the pressure exerted by the springs against the piston 4 and plunger 3. This means comprises suitable tensioning discs 8 which engage the ends of the springs remote from the piston 4 and which threadably receive cap screws 9 carried by the head 7. Thus by adjustment of the cap screws the tension of the springs 6 may be regulated.

The plunger 3 and piston 4 are connected for limited relative movement to absorb shocks by means of a stud 10, which is welded or otherwise suitably connected or attached to the upper head 11 of the plunger and extends slideably through a central opening 12 in the piston 4. A nut 13 is threaded upon the end of the stud projecting above the piston 4 and a spring 14 is positioned between the nut 13 and the piston 4 to permit limited relative movement of the piston 4 and plunger 3 and to maintain these members in proper engagement at all times. The stud 10 is provided with a longitudinal bore 15 to permit equalization of air pressure in the enlarged section 5 of the cylinder and the interior of the plunger 3.

The piston 4 has piston rings 16 carried thereby to provide a relatively tight seal between the piston and the walls of the enlarged section 5 of the cylinder structure for the purpose of providing an air cushion for the downward movement of the piston 4. The space 20 below the piston 4 and the lower head of the enlarged section 5 of the cylinder is open to atmosphere through a connection 17, having a valve 18 of any approved construction therein. An orifice disc 19 is placed in the connection 17 to atmosphere for the purpose of retarding the expelling of air from the space 20 during the downward movement of the piston 4 so as to provide the air cushion for the downward movement of the piston.

The plunger 3 is of the differential type, providing an air space 21 between a part of the plunger and the inner wall of the cylinder 1. This differential space 21 is connected to the suction of the pump (not shown) which delivers the pressure fluid through the pipe line (not shown) by the connection 22 and to atmosphere through a bleeder valve 23. An air chamber 24 is also connected with the differential space

or chamber 21 to prevent creation of an excessive vacuum in this differential space. The line 22 leading to the suction of the pump has a check valve 25 therein so that any leakage passing the piston rings of the plunger is conducted back to the suction line of the pump. This check valve 25 prevents the flow of liquid from the suction of the pump to the differential chamber 21 when the pressure in the pump suction is higher than the pressure in the differential chamber. The upper end of the plunger 3 is packed, as shown at 26, so as to prevent any leakage past the piston rings 27, which are carried by the plunger, from getting into the enlarged portion 5 of the cylinder.

The lower end of the plunger 3 has its periphery cut away to provide an annular recess for the reception of the piston rings 27. Each piston ring 27 is carried by an individual retainer 28, as clearly shown in Figure 3 of the drawings, and certain of the piston rings have line pressure, i. e., the pressure of the liquid flowing through the line with which the equalizer is connected, back of them to insure high pressure contact with the cylinder wall. All of the piston rings 27 and their individual retainers 28 are held in place by a cover plate 29 which fits against the lower end of the plunger 3 and has an annular flange 30 extending into the piston ring receiving space. The cover plate 29 is yieldably connected to the plunger by means of a set screw 31 and a spring 32, as clearly shown in Figure 1 of the drawings, insuring continuous clearance on the side of the piston rings.

The lower head 33 of the plunger 3 is provided with a cross passage 34 therein which opens out into suitable openings or passages 35 formed in the lowermost piston ring retainer 28. Pressure fluid from the line (not shown) is delivered to the passages 34 and 35 and against the back of the lowermost piston ring 27 through a suitable passage 36 formed in the cover plate 29 and the plunger head 33.

An atmospheric vent 37 opens into the packing 26.

Suitable lubrication of the equalizer is provided through a lubricating line 40 and air is admitted into the interior of the enlarged section 5 of the cylinder through an air cleaner 41 and an air line 42.

The valve 18 in the bleeder line to the air cushion space 20 together with the orifice plate 19 permits regulation of the sensitivity of the pressure equalizer on sudden changes in pressure and the relief valve or check valve 23 is provided in the line 22 which communicates with the suction of the pump to relieve any liquid in the differential chamber 21 should the check valve 25 become inoperative.

The stud 10 and its manner of establishing connection between the plunger 3 and the piston 4, as heretofore described, will allow for slight variations in the cylinder walls and the walls of the enlarged section 5 of the cylinder structure without excessive friction and in effect allows the piston 4 to float freely, independently of the plunger 3, which is acted upon by the pressure liquid in the line.

It will be understood that the invention is not to be limited to the specific construction or arrangement of parts shown, but that they may be widely modified within the invention defined by the claims.

What is claimed is:

1. In a pressure equalizer, a cylinder, a plunger

in said cylinder and adapted to be acted upon by the liquid the pressure of which is to be equalized, a spring pressed piston connected to said plunger, springs acting on said piston in opposition to liquid pressure against said plunger, yieldable means connecting said plunger and piston to provide connected movement of the piston and plunger in either direction and allow limited relative movement of the plunger and piston, means for regulating the tension of said springs to regulate the pressure opposing pressure exerted on said plunger, said piston moving in said cylinder and arranged to provide an air space in opposition to the action of said springs, and means controlling the air in said space to provide a regulatable air cushion for the piston.

2. In a pressure equalizer, a cylinder, a plunger in said cylinder and adapted to be acted upon by the liquid the pressure of which is to be equalized, a spring pressed piston connected to said plunger, springs acting on said piston in opposition to liquid pressure against said plunger, yieldable means connecting said plunger and piston to allow limited relative movement of the plunger and piston, means for regulating the tension of said springs to regulate the pressure opposing pressure exerted on said plunger, said piston moving in said cylinder and arranged to provide an air space in opposition to the action of said springs, means controlling the air in said space to provide a regulatable air cushion for the piston, said plunger being provided with opposed differential areas one of which is subject to pressure lower than the liquid pressure acting upon the other area.

3. In a pressure equalizer, a cylinder, a plunger in said cylinder and adapted to be acted upon by the liquid the pressure of which is to be equalized, a spring pressed piston connected to said plunger, springs acting on said piston in opposition to liquid pressure against said plunger, said plunger comprising a body shell and a cover plate engaged by the pressure liquid, means yieldably connecting said cover plate to said shell, said shell having a differential area thereon opposed to said cover plate, means for subjecting said differential area to air pressure, and a safety valve connected to the differential chamber formed by said differential area between the shell and cylinder to permit the escape of fluid from the differential chamber when pressure therein rises above a predetermined degree.

4. In a pressure equalizer, a cylinder, a plunger in said cylinder and adapted to be acted upon by the liquid the pressure of which is to be equalized, a spring pressed piston connected to said plunger, springs acting on said piston in opposition to liquid pressure against said plunger, said plunger having opposed differential areas one of which is subjected to pressure lower than the liquid pressure acting upon the other area, a connection to the differential chamber formed by said differential area between the plunger and cylinder and adapted to be connected to the suction of a pump the discharge liquid pressure of which acts upon the plunger, and a check valve in said connection whereby when the pressure in said differential chamber exceeds the suction pressure of the pump the pump will drain said chamber.

5. In a pressure equalizer, a cylinder, a plunger in said cylinder, said plunger having opposed differential areas one of which is subjected to pressure of fluid the pressure of which is to be equalized, said cylinder and plunger constructed

and arranged to provide an air chamber facing the other of said differential areas, said air chamber open to atmosphere, yieldable sealing means carried by said plunger and acted upon by pressure of the fluid whose pressure is to be equalized to prevent leakage of fluid into said air chamber, and a safety valve connected to said air chamber to permit escape of air from the air chamber when pressure therein rises above a predetermined degree.

6. In a pressure equalizer, a cylinder, a plunger in said cylinder and adapted to be acted upon by the fluid the pressure of which is to be equalized, a spring-pressed piston connected to said plunger, springs acting upon said piston in opposition to liquid pressure against the plunger, said piston and cylinder constructed and arranged to provide an air space in opposition to the action of said springs, said plunger having opposed differential areas one of which is subjected to pressure of fluid the pressure of which is to be equalized, said cylinder and plunger constructed and arranged to provide an air chamber facing the other of said differential areas, said chamber open to atmosphere whereby said other differential area will be subjected to atmospheric pressure, and means for controlling the air in said air space to permit regulation of the

air cushion for the piston proportionate to the differential of the pressures acting upon the differential areas of the plunger.

7. In a pressure equalizer, a cylinder, a plunger 5 in said cylinder and adapted to be acted upon by the fluid the pressure of which is to be equalized, a spring-pressed piston connected to said plunger, springs acting upon said piston in opposition to liquid pressure against the plunger, 10 said piston and cylinder constructed and arranged to provide an air space in opposition to the action of said springs, said plunger having opposed differential areas one of which is subjected to pressure of fluid the pressure of which is to be equalized, said cylinder and plunger constructed and arranged to provide an air chamber 15 facing the other of said differential areas, said chamber open to atmosphere whereby said other differential area will be subjected to atmospheric pressure, means for controlling the air in said air space to permit regulation of the air cushion for the piston proportionate to the differential of the pressures acting upon the differential areas of the plunger, and yieldable sealing means carried by said plunger and acted upon by pressure 20 of the fluid whose pressure is to be equalized to prevent leakage of fluid into said air chamber.
